(57) **CLAIM**

The ornamental design for a dual screen display as shown and described.

DESCRIPTION

FIG. 1 is a perspective view of a dual screen display showing my new design;

FIG. 2 is another perspective view thereof;

FIG. 3 is a front elevational view thereof;

FIG. 4 is a rear elevational view thereof;

FIG. 5 is an enlarged left side elevational view thereof;

FIG. 6 is an enlarged right side elevational view thereof;

FIG. 7 is a top plan view thereof;

FIG. 8 is a bottom plan view thereof;

FIG. 9 is an enlarged view of portion '9' shown in FIG. 1;

FIG. 10 is an enlarged view of portion '10' shown in FIG. 2;

FIG. 11 is an enlarged view of portion '11' shown in FIG. 4;

FIG. 12 is an enlarged view of portion '12' shown in FIG. 7;

FIG. 13 is an enlarged view of portion '13' shown in FIG. 8; and,

FIG. 14 is an enlarged view of portion '14' shown in FIG. 8.

The even-dash broken lines in the drawings depict portions of the dual screen display that form no part of the claimed design.

The dot-dash broken lines in FIGS. 1, 2, 4 and 7-14 represent the extents of the detail views and form no part of the claim. The unshaded surfaces, shown between the broken lines and the solid lines, seen in FIGS. 3, 8, and 13, form no part of the claimed design.
